UNITED STATES PATENT OFFICE.

SAMUEL ROUSH, OF NEWARK, INDIANA.

WINDOW-PANE FASTENER.

No. 911,164.

Specification of Letters Patent.

Patented Feb. 2, 1909.

Application filed May 29, 1908. Serial No. 435,803.

To all whom it may concern:

Be it known that I, SAMUEL ROUSH, a citizen of the United States, residing at Newark, in the county of Green, State of Indiana, have invented certain new and useful Improvements in Window-Pane Fasteners; and I do hereby declare the following to be a full, clear, and exact description of the invention, such as will enable others skilled in the art to which it appertains to make and use the same.

This invention relates to window pane fastening devices and in carrying out my invention I have in view the obviation of the employment of putty for securing the pane in place and further have in view provision of a window pane fastening strip which may be placed upon the market and sold by itself and which may be applied to any ordinary window sash now in use without in any way altering the construction of the sash such as by forming grooves or the like therein.

One of the salient features of my invention resides in so constructing the pane securing strip that when secured in place, a portion of each strip will be forced against the pane and the pane in this manner firmly held in place. This result is obtained by forming the device of a strip of sheet metal one edge portion of which is bent to extend normally at right angles with respect to the body of the strip, the other edge being bent at an acute angle with respect to the said body of the strip and having its free edge resting against the adjacent face of the first mentioned right angularly bent edge, and, by driving fastening devices such as tacks or small nails through the edge portion of the strip which is bent at an acute angle to the body portion, through the body portion, and into the sash it being understood that when this is done, the last mentioned bent edge portion will be compressed in the direction of the body of the strip and will serve to spring the first mentioned bent edge portion firmly against the adjacent face of the window pane.

Another feature of the invention resides in providing corner keys for connecting the strips at their corners and in this manner rendering the structure more secure.

In the accompanying drawings, Figure 1 is a front elevation of the upper portion of a window sash showing the application of my invention thereto, Fig. 2 is a horizontal sectional view through one of the stiles of

the sash, the device itself, and the pane of glass secured in place thereby, Fig. 3 is a view similar to Fig. 2 but exaggerated and showing in full lines the normal position of the strip and its bent edge portions and in dotted lines their position when the strip is attached or secured to the window sash, Fig. 4 is a vertical sectional view in detail through the upper corner of a window sash and strips secured thereto showing the manner of connecting the strips at their upper ends.

In the drawings, there is illustrated a portion of a window sash, the stile being indicated by the numeral 5 and the upper rail by the numeral 6, the said stile and rail being formed each with a rabbet 7 in which rabbits are received the side and upper edges of a pane 8 of glass.

The pan securing device embodying my invention is in the form of a strip 9 of resilient sheet metal which has one edge portion, throughout its length, bent at right angles as indicated by the numeral 10 and of less width than the portion 9 and has its other edge portion bent at an acute angle as indicated by the numeral 11 the last mentioned portion being of greater width than either of the portions 9 and 10 and having its free or outer edge resting directly against the inner or adjacent face of the portion 10 at the free edge thereof. Each of the devices is formed through its body portion 9 and its bent edge portion 11 with a number of openings 12 through which tacks or nails 13 are to be driven to secure the devices to the stiles and rails of the sash.

In applying the devices embodying my invention to the window sash, the lengths of strips are disposed in position with their portions 10 resting directly against the edge portions of the pane to be secured in place and their body portions 9 directly against that wall of the rabbet other than the one against which the pane rests. While the strips are firmly held in place, the nails 13 are driven through their portions 9 and 11 and into the said wall of the rabbet the strips being in this manner secured in place.

It will be understood and observed from the drawings that as the nails are driven into place, the portion 11 of each of the strips will be compressed in the direction of the body portion 9, as shown by dotted lines in Fig. 3 of the drawings, and that this compression of the said portion 11 will result in a strain

being placed upon the portion 10 tending to spring it from its normal position, the springing of this portion 10 serving to spring it firmly against the pane of glass and more firmly hold the same in place and thereby prevent rattling of the pane in windy weather or when the window sash is raised or lowered.

In order to securely hold the several strips 10 surrounding the pane and the opening in which the pane is received, in proper relative position, I provide corner keys each of which is in the form of a flat strip of sheet metal bent to form right angularly extended portions 14 one portion being inserted in the one end of one member and in the adjacent or meeting end of another member the extremities of all the members or strips being beveled as indicated by the numeral 15. The 20 employment of such corner keys is extremely desirable where the side or vertical strips are to be disposed against thin mullions as it will be difficult to drive nails through such mullions without splitting them, that is nails 25 large enough to securely hold the said strips in place.

What is claimed is:

1. A fastening strip for window panes consisting of a resilient metal plate having one 30 longitudinal edge portion bent up inwardly at a right angle and the opposite longitudinal edge portion bent up at an acute angle and

resting with its free longitudinal edge against the adjacent face of the first named bent up portion and at an acute angle thereto, said 35 plate having perforations through its body and the second named bent up portion for the passage of fastening devices.

2. The combination with a window sash having a pane receiving rabbet and a pane 40 therein, of a pane securing strip disposed against one side of the rabbet, the said strip having its edge adjacent the pane bent to extend at a normal right angle and having its other edge bent to extend at an acute angle 45 with its free edge portion resting against the inner face of the first mentioned bent edge portion, and securing devices driven through the last mentioned angularly bent edge portion and through the strip said strip 50 being formed of resilient sheet metal whereby compression of the last mentioned edge portion in the direction of the body of the strip through the medium of the fastening devices will act to spring the first mentioned right 55 angularly bent edge portion firmly against the adjacent face of the pane.

In testimony whereof, I affix my signature, in presence of two witnesses.

SAMUEL ROUSH.
